UNITED STATES PATENT OFFICE.

JOHN BURRY, OF NEW YORK, N. Y., ASSIGNOR OF TWO-THIRDS TO JAMES E. MUNSON AND ALOYS WIRSCHING, BOTH OF SAME PLACE.

TELEGRAPH.

SPECIFICATION forming part of Letters Patent No. 404,165, dated May 28, 1889.

Application filed June 8, 1888. Serial No. 276,475. (No model.)

To all whom it may concern:

Be it known that I, JOHN BURRY, a citizen of the United States, residing at New York, county of New York, and State of New York, 5 have invented certain new and useful Improvements in Electric Telegraphs, fully described and represented in the following specification and the accompanying drawings, forming a part of the same.

10 This invention relates to an apparatus which is designed for use in those cases where it is desired to energize any one of a large number of electro-magnets located at a distant point.

15 The invention is applicable to a great variety of uses, but is especially applicable to type-writers, type-setting machines, printing-telegraphs, and analogous instruments.

20 A full understanding of the invention can best be given by an illustration and a detailed description of an instrument embodying the same. All preliminary description will therefore be omitted and a full description given, reference being had to the accompanying 25 drawings, in which—

25 Figure 1 is a plan view of an instrument embodying the invention in what I regard as its best form. Fig. 2 is a sectional elevation of the same, taken upon the line 2 of Fig. 1. 30 Fig. 3 is a diagram illustrating the system of electrical connections. Figs. 4 to 11 illustrate modified organizations, which will be herein-after described.

35 Referring particularly to Figs. 1 to 3, it is to be understood that 1 to 8, inclusive, represent a number of electro-magnets termed “working-magnets,” which it is desired to energize in proper order to operate any mechanism—such, for example, as the type-bars 40 or type wheel of a type-writer or printing-telegraph. These magnets are included in a corresponding number of branches, *a* to *h*, inclusive, of an auxiliary circuit, *i*, which may be a local circuit including a local battery, 9, 45 or may be a branch of the main circuit, as will be presently explained. The circuit *i* is provided with two branches, *k* *l*, which include circuit-closers 10 11, and also switches 13 14, by which the branches can be respectively connected to either of two branches, *m* 50 *n* and *o* *p*, which latter branches are in turn

provided with switches 15 16 17 18, by which they can be respectively connected to either of the branches *a* *b*, *c* *d*, *e* *f*, and *g* *h*. By this means it becomes possible, as will readily be seen, to close the auxiliary circuit through either one of the working-magnets.

55 The circuit-closers 10 11 are operated by means of a polarized relay, *A*, which is included in the main circuit *B*, leading from the 60 distant point from which it is desired to energize the working-magnets. The relay *A* may be of the ordinary form, consisting of an electro-magnet having a polarized armature; but as herein shown it is composed of two 65 helices, 20, which are wound in reverse directions, as indicated in Fig. 3, and are provided at their opposite ends with polarized armatures 19, which carry the movable members of the circuit-closers 10 11. The operation of 70 the relay is such by reason of the reverse winding of its helices that whenever a current of one polarity is caused to pass over the circuit *B* one of the armatures 19 will be attracted and the other repelled, thereby closing 75 the circuit through one of the branches (*k* or *l*, as the case may be) and breaking the circuit through the other, and vice versa. In order, therefore, to close the circuit through one or the other of the branches *k* *l*, as may 80 be desired, it is only necessary to cause the current passing over the main circuit *B* to be of the required polarity to attract the armature carrying the circuit-closer for that branch, and in order to close the circuit 85 through the branches *k* *l* alternately, or in any desired order of succession, it is only necessary to change the polarity of the current passing over the main circuit.

90 The armatures 19 are provided with springs or other retractiles, 21, by which they are normally held in position to break the circuit through both of the branches *k* *l*.

95 For the purpose of operating the relay to attract its respective armatures the main circuit *B* may be provided at the transmitting-station with any suitable form of circuit making and breaking device, and for the purpose of changing the polarity of the current the circuit may be provided with any of the ordinary forms of pole-changer. These devices 100 are well known in the art, and therefore need

no specific description. They form no part of the present invention, and are therefore not illustrated in the present case.

The auxiliary circuit *i* is provided with 5 branches *q r s t*, also forming auxiliary circuits which include electro-magnets C D E F, termed "switch-magnets," and connected with the switches 13, &c., in such manner that the latter form circuit-closers M N for these auxiliary circuits. The switches 13 14 and 15 16 10 17 18 are connected, respectively, to sliding switch-bars 22 23, which are arranged to be normally held in a mid-position by means of springs or other retractiles, 24, and are provided at their opposite ends with pivoted arms 15 25, having shoulders which are arranged to be engaged by catches 26, formed upon the armatures 27 of the magnets C D E F, when the latter are rocked inward by the energizing of 20 the magnets.

The armatures 27 are provided with back-stops 28 and with retractiles 29, by which, whenever either one of the armatures has 25 been rocked inward by the energizing of its magnet and has engaged with the shoulder upon the arm 25, it will upon the de-energizing of the magnet be moved outward against the back-stop, thereby moving the bar (22 or 23, as the case may be) and shifting the 30 switches to which the bar is connected, so as to break the circuit through the magnet and at the same time connect the switches with the branches *m n*, &c., or *a b*, &c., as the case may be.

35 The operation of the apparatus as thus far described is as follows: In describing this operation it will be assumed that in order to energize the relay A to operate the circuit-closer 10 it is necessary to send over the circuit B what may be termed a "+ current," and that to energize the relay to operate the circuit-closer 11 what may be termed a "- current" is required. Assuming now that it is desired in the transmission of a message or for any 40 other purpose to energize the magnet 1, the operator at the sending-station will cause a + current to pass over the circuit B. This will energize the relay and operate the circuit-closer 10 to close the auxiliary circuit 45 through the magnet C, thereby rocking its armature 27 inward, so as to cause its catch 26 to engage with the shoulder upon the arm 25 of the bar 22. As soon as the circuit B is broken by the operator the spring 21 will 50 operate the circuit-closer 10 to break the auxiliary circuit, and thus de-energize the magnet C. As soon as this is done the spring 29 will rock the armature 27 of that magnet back to its normal position, and thus 55 shift the bar 22, so as to cause the switches 13 14 to connect with the branches *m o*. The operator will then cause a second + current to pass over the circuit B, thereby again operating the circuit-closer 10 to close 60 the circuit; but the switch 13 having been shifted so as to connect with the branch *m* the circuit will be closed through the magnet 65

E, thereby rocking its armature 27 inward, so as to cause its catch 26 to engage with the shoulder upon the arm 25 of the bar 23. As 70 soon as the circuit B is broken after the second + current, the circuit-closer 10 will be operated to break the circuit, and thereby de-energize the magnet E, and the spring 29 of the armature of that magnet will then rock 75 the armature so as to shift the bar 23 and switches 15 16 17 18, so as to cause the switch 15 to connect with the branch *a*. The operator will then cause a third + current to pass over the circuit B, thereby again operating 80 the circuit-closer 10; but the switches 13 15 being then connected to the branches *m a*, the magnet 1 will be energized and will perform its work. Located in the circuit *i*, between the branch *q* and the working-magnets, is a magnet, G, termed a "releasing-magnet," the armature 30 of which is connected to a lever, 31, which is arranged to engage with a toe, 32, extending from a rock-shaft, 33, having toes 34, which extend beneath the 90 ends of the arms 25 in such manner that when the toes 34 are rocked upward they will engage with the arms and disengage the latter from the catches 26, thereby releasing the bars 22 23 and permitting them to be restored 95 to their normal or mid position by their springs 24. The shaft 33 is provided with an arm, 35, which is connected by a rod, 36, with a similar arm extending from a similar shaft, 33, located upon the opposite side of the instrument and having similar toes, 34, arranged 100 to engage with the arms 25 at that side of the instrument. The shafts 33 are connected to springs 37, which operate to normally hold the shafts in such position that the toes 34 will 105 be slightly below the ends of the arms 25. As the third + current is sent over the line B and the auxiliary circuit is closed to energize the magnet 1, the magnet G will be energized and the lever 31 will be rocked outward, so as to engage with and pass the toe 32, as indicated by dotted lines in Fig. 2. As 110 soon as the circuit B is broken after sending the third + current, and the circuit-closer 10 is thereby operated to break the circuit 115 through the branch *k*, the magnets 1 and G will be de-energized and the lever 31 will be restored to its normal position by its retractile 38. In being restored to its normal position it will engage with the toe 32 and rock 120 the shafts 33 and toes 34, so as to cause the toes to engage with the arms 25 and release the latter from the catches 26, and thereby permit the bars 22 23 and the switches to be restored to their normal position, as just explained. 125

It will thus be seen that in order to energize the magnet 1 and cause it to perform its work it is necessary in the organization which has just been described to cause three + impulses to pass over the circuit B, two of said impulses operating to select the magnet and the third causing it to be energized.

If, instead of energizing the magnet 1, it is

desired to energize the magnet 2, the operation will be exactly the same, except that the second impulse will be — instead of +, thereby causing the relay to operate the circuit-closer 11, to close the circuit through the branch *l*, and the switch 14 having been shifted by the previous + impulse, so as to connect with the branch *o*, the auxiliary circuit will be closed through *l o t r*, so as to energize the magnet *F*, and thereby, when the circuit is broken by the circuit-closer 11, cause the bar 23 to be moved so as to connect the switch 15 with the branch *b* instead of with the branch *a*, and so the several magnets may be energized in succession or in any desired order by causing + and — impulses to pass over the circuit *B* in the proper order. Thus, to energize magnet 1 the impulses will be + + +; to energize the magnet 2, + — +; for magnet 3, — + +; for magnet 4, — — +; for magnet 5, + + —; for magnet 6, + — —; for magnet 7, — + —; for magnet 8, — — —.

The instrument, as herein shown and as has been described, is capacitated to make selection between and energize but eight different magnets, as this number is sufficient to fully illustrate the principle and operation of the invention. In the practical operation of the system it will usually be necessary to employ a larger number than this, and where that is necessary it can readily be accomplished by a simple addition to the system which has been described. If, for example, sixteen magnets are required, the branches *a b c*, &c., will be connected to eight switches similar to the switches 15 16, &c., which will be operated by a pair of magnets similar to the magnets *E F*, and in the same manner, and will operate to make connection with sixteen branches leading to the sixteen magnets. In such case it will be necessary to transmit three impulses over the main circuit to effect the proper selection and a fourth impulse to cause the energizing of the selected magnet; or, if it is desired to employ thirty-two magnets, a fourth set of switches will be employed in the same manner, and in such case it will be necessary to transmit four impulses to effect the proper selection and a fifth to energize the selected magnet, and by pursuing this system the number of magnets can be multiplied indefinitely without in any wise adding to the complication of the system.

In some cases it will be preferable to so organize the system that the switch-bars 22 23 will each operate the same number of switches, so that the work performed by each of the switch-magnets will be equal. This may be accomplished by organizing the system as illustrated in Fig. 4, in which the switches 16 17 are operated by a third switch-bar, 39, which is equipped the same as the bars 22 23, and is controlled by a pair of switch-magnets, *I K*, which are included in auxiliary circuits formed in part by branches *u v*, which connect with the switches 16 17 and with the branches *s t*. By this means the work done

by each of the switch-magnets is equal and is reduced to the minimum. When the system includes only a comparatively small number 70 of the working-magnets—as, for example, only eight—the maximum number of switches operated by any one magnet is only four, and this number is not so large as to make the work of the magnet unduly heavy; but where 75 the system includes sixteen or more working-magnets the maximum number of switches operated by one magnet in the organization first described would be eight or more, and this number would in some cases put too 80 much work upon the magnet.

The operation of the system when organized as shown in Fig. 4 is substantially the same as already described, except that the branches *m n o p* and *a b*, &c., are so connected that the order of the + and — currents over the main circuit required to energize the respective magnets 1 2, &c., is somewhat different. To illustrate: To energize magnet 1 will require a — impulse, which will operate 90 to connect the switch 13 to the branch *m*, then a + impulse to connect the switch 15 to the branch *a*, and then a second + impulse to energize the magnet 1. To energize magnet 2 will require — +; for magnet 3, + 95 + +; for magnet 4, + — +; for magnet 5, + + —; for magnet 6, + — —; for magnet 7, — + —; for magnet 8, — — —.

It may in some cases be preferable, particularly where the system is to be operated 100 over short or comparatively short lines, to energize the magnets *C D E F* and *1 2*, &c., directly from the main circuit *B* instead of by a local circuit, and in such case the auxiliary circuits will be simply branches of the 105 main circuit. If desired, this can be done as illustrated in Fig. 5. In this case the local battery 9 is dispensed with and the auxiliary circuits are connected to and form branches of the main circuit *B*. Between the points 110 where the branches *i* and *k l* connect with the main circuit the main circuit is provided with a resistance-coil, *H*, or any other suitable form of resistance which is sufficient to shunt the current or the main part of the 115 current through the branches *i k* or *i l*, as the case may be, whenever either of those branches is closed by the operation of the circuit-closers 10 11.

The operation of the system when thus organized is as follows: When a + current is sent over the main circuit, the circuit-closer 10 will be operated the same as already described, so as to close the branch *k*, and the current over the main circuit will then by 120 reason of the resistance *H* be shunted so as to pass through the branches *k i* and their connections, and thus energize the magnets *C* or *E*, or one of the magnets *1 2*, &c., and *G*, as the case may be, the same as before described. 125 When a — current is sent over the main circuit *B*, the circuit-closer 11 will be operated so as to close the branch *l* and shunt the current over the main circuit through the branches

l i and their connections with a corresponding effect.

It will readily be seen that the branches *i k l* of the system, as illustrated in Fig. 4, 5 may be connected to the main circuit—that circuit being provided with the resistance *H*—so as to dispense with the local battery and circuit in the same manner.

In the system as thus far described it is 10 necessary in order to select and energize any one of eight magnets to transmit three impulses over the main circuit *B*, and to select and energize any one of sixteen magnets to transmit four impulses, and for thirty-two 15 magnets, five impulses, and so on. This may in some cases make the operation of the system slower than is desirable. When greater speed is desired, it may be obtained by varying the strength of the current over the main 20 circuit in addition to changing its polarity, and by this means any one of thirty-two magnets may be selected and energized by transmitting three impulses over the circuit, or by transmitting four impulses any one of one 25 hundred and twenty-eight magnets may be selected and energized, and so on. An organization of this character is illustrated in Fig. 3. In this case the local circuit and battery are dispensed with the same as in the organization shown in Fig. 5. The four branches *m n o p* are connected to switches 13^a , &c., which are arranged to connect with eight branches, *m'*, &c., which are in turn connected to eight switches, 15 15^a , &c., corresponding to 30 the switches 15 , &c., of the organizations already described. The switches 15 , &c., normally connect with the branches *s t*, and are arranged to connect with sixteen branches, *a a'*, &c., corresponding to the branches *a*, &c., 35 of the other organizations described. The branches *a a'*, &c., are connected to sixteen switches, 15^b , &c., which are arranged to connect with thirty-two branches, *a²*, &c., which connect with the branch *i* and include the 40 thirty-two magnets $1 1^a$, &c. The switches 13^a , &c., and 15^b , &c., are operated through switch-bars 22^a 23^a , which are controlled by magnets *C' D' E' F'*, which are included with the magnets *C D E F* in the respective 45 branches *q r s t*, so that when the circuit is closed through either one of the branches the current will pass through both of the magnets included in that branch. The retractiles of the armatures of the two magnets included in 50 each branch are, however, so adjusted that the magnets must be energized to different extents in order to overcome the retractiles and move their armatures. From this it results that by causing a relatively-weak current to pass over the circuit the magnets *C D E F* may be energized sufficiently to move 55 their armatures without energizing the magnets *C' D' E' F'* sufficiently for that purpose, while if a relatively-strong current is caused 60 to pass over the circuit both magnets will be energized sufficiently to move their armatures.

The operation of the system when thus organized is as follows: To energize the magnet *1*, there will be sent over the circuit three + 70 impulses. The first impulse will be of full strength, so as to energize both the magnets *C C'* and connect the switch 13 with the branch *m* and the switch 13^a with the branch *m'*. The second impulse will also be of full 75 strength, and will operate to energize both the magnets *E E'* and connect the switch 15 with the branch *a* and the switch 15^b with the branch *a²*. The third impulse will operate to energize the magnets *1* and *G* the same as before described. To energize magnet 1^a , the operation will be the same, except that the second impulse will be of less strength, so as to energize only the magnet *E*, thus leaving the switch 15^b connected to the branch *a²*, and in this manner by combining + and - impulses of opposite polarity and of greater and less strength each of the thirty-two magnets $1 1^a$, &c., can be selected and energized by 80 three impulses over the line; or the magnets, 85 instead of being energized to operate by different strengths of current, may be controlled by the length of duration of the impulse, and thus the same result be effected.

In some cases it may be desirable to decrease the number of magnets employed for operating the switches 13 14 15 , &c., and this can be accomplished by so organizing the system that it will be necessary to move the switch-bars 22 23 in but one direction. An 100 organization of this character is illustrated in Figs. 7, 8, 9, and 10. In this organization the magnets *D F* are omitted and the switches are arranged to normally maintain connection with the branches *n p b d f h*, and the magnets *C E* and the connections with the switch-bars are so arranged that the switches are shifted when the magnets are energized instead of when they are de-energized. For this purpose the branches *q s*, which include the 105 magnets *C E*, instead of connecting with the switches 13 15 , &c., when the latter are in their normal position, connect with the circuit *i*, and include circuit-closers *M N*, which are operated at the proper times to close the 110 local circuit through the branches *q s*, and thus energize the magnets *C E* to operate the switches. The circuit-closers *M N* may be of a variety of forms; but as illustrated in the 115 present case they consist of contact-pins 40, extending from a shaft, 41, which is connected to one wire of the circuit *i*, and contact fingers or brushes 42, which are connected to the branches *q s*, and are arranged to make contact with the pins 40 at the proper times as 120 the shaft 41 is revolved. The shaft 41 is provided with a third circuit-closer, *O*, consisting of similar pins, 40, projecting from the shaft, and a similar brush or finger, 42, connected to the other wire of the circuit *i*. For 125 the purpose of operating the circuit-closers *M N O* the shaft 41 is provided with a ratchet, 43, having a holding-pawl, 44, and engaged by a driving-pawl, 45, carried by the arma- 130

ture-lever 46 of an electro-magnet, P, termed an "auxiliary" magnet, which is included in the circuit *i*. The lever 46 is acted on by the magnet P, so as to retract the pawl 45 upon the ratchet, and by a retractile, 47, so as to advance the pawl and give a partial turn to the ratchet and the shaft 41 when the magnet is de-energized. The connections for operating the switches 13, &c., are in this case so arranged that the switches are shifted when the magnets are energized, and for this purpose the armature-levers 27 of the magnets are connected directly (see Fig. 9) to the arms 25 of the switch-bars, and the arms 25 are provided with pivoted hooks 48, which, when the magnets are energized, engage with a stationary catch, 26, and hold the bars and switches in the position to which they have been shifted. The armature-lever 31 of the magnet G is in this case connected to the shaft 33, the toes 34 of which engage with the hooks 48 and release them from the catch 26 whenever the magnet G is energized. The magnet G, instead of being located in the circuit *i*, is located in a branch, *w*, which includes a circuit-closer, R, also operated by the shaft 41. For this purpose one wire of the branch *w* is connected to a weighted lever, 49, having a finger, 50, which is so arranged that when the lever is depressed it enters a small cup of mercury or other conducting liquid, 51, to which the other wire of the branch is connected. The shaft 41 is provided with two pins, 52, which at the proper times engage with a lip, 53, of insulating material, upon the lever 49 and rock the lever, so as to form contact between the finger 50 and mercury, 51, and thus close the circuit *i* through the branch *w* and energize the magnet G. The branch *l* and circuit *i* are connected by a branch, *y*, which includes a resistance-coil or other resistance, L, and also a circuit-closer, S, also operated by the shaft 41 and arranged to maintain the branch *y* in a closed condition, except at such times as it is required to close the circuit *i* to energize one of the magnets 1, 2, &c. This circuit-closer consists of a notched disk, 54, carried by the shaft 41, and a brush or finger, 55, the end of which rests upon the disk and to which the branch *y* is connected.

The operation of the system when thus organized is as follows: When the system is in its normal condition, the circuit-closer M will be in position to close the circuit *i* through the branch *q*, and the circuit-closer S will be in position to close the circuit *i* through the branch *y*. To energize the magnet 1, three + impulses will be sent over the main circuit. The first impulse will operate the circuit-closer 10 to close the circuit *i* through the branches *h* *q*, and, the branch *q* being closed by the circuit-closer M, the magnet C will be energized, and will act to shift the switch 13 into connection with the branch *m*, in which position it will be held by the hook 48, and at the same time the magnet P will be energized and will act to retract the pawl 45.

As soon as the magnets C P are de-energized by the breaking of the main circuit and the branch *k*, the retractile 47 of the armature-lever 50 will cause the pawl 45 to engage with the ratchet 43 and give a partial turn to the shaft 41. This will operate the circuit-closer M, so as to break the branch *q*, and at the same time operate the circuit-closer N, so as to close the circuit through the branch *s*. The second + impulse will then pass through the branches *k* *q* *s*, thereby energizing the magnets E P, so as to shift the switch 15 into connection with the branch *a*, and when the circuit is broken after the second impulse the pawl 45 will move the circuit-closer N, so as to break the circuit through the branch *s*, and at the same time move the circuit-closers O S to close the circuit *i* and break the circuit through the branch *y*. The third + impulse will then pass through *k* *m* *a*, so as to energize the magnets 1 and P, so that the magnet 1 will perform its work, and when the circuit is broken after the third impulse the pawl 45 will move the circuit-closers O M S, so as to break the circuit *i* and close the branches *q* and *y*, and at the same time the circuit-closer R will be operated to temporarily close the branch *w*, and thus temporarily energize the magnet G and cause it to operate to release the hooks 48 and permit the springs 24 to restore the switches 13, &c., to their normal positions in connection with the branches *n* *p*, &c. To select and energize the magnet *h*, for example, three - impulses will be required. The first impulse will operate the circuit-closer 11 to close the branch *l*; but the circuit *i* being broken at the circuit-closer O the magnet *h* will not be energized, but the current over the local circuit will pass through the branch *y* and simply energize the magnet P and move the circuit-closers M N O S, and the second - impulse will act in the same manner; but when the circuit is broken and the magnet P de-energized and the circuit-closers M N O S moved after the second impulse the circuit-closers O S will be brought into position to close the circuit *i* and break the branch *y*, as before, so that upon the third - impulse the current over the local circuit will pass through the magnet *h* and energize it to do its work. From this it will be seen that it is only at each third impulse that the local circuit *i* is closed by the circuit-closer O, and that as a consequence it is only each third impulse that is permitted to pass through and energize the selected magnet. It is this feature which permits the switches 13, &c., to be normally in connection with the branches *n* *p*, &c. The resistance L is introduced into the branch *y* to balance the resistance of the magnets C E, so that when the current is sent through the branch *y* it will energize the magnet P to only the same or about the same degree that it is energized when the current is sent through the branches *q* *s* and magnets C E.

It will be observed that in the organization

which has just been described, when the circuit-closer 10 is operated to close the circuit through i k q or i k s to energize the magnets C E, the circuit will also at the same time be closed through i k n or m b or d f or h o or p , l , and y , thus shunting a certain part of the current around the magnet C or E, as the case may be. The amount of resistance in the shunt-circuit thus formed will, however, be so great that the magnet C or E will be sufficiently energized to perform its work; but if in any case this should prove objectionable it may be overcome by providing the branch l with a circuit-closer similar to the circuit-closers M N, which will operate to close the branch only at each third impulse. It will be preferable in nearly all cases to employ but a single main circuit, B; but if in any case it is feasible or desirable to employ two independent main circuits, then the polarized relay A can be omitted and the circuit-closers 10 11 operated by ordinary magnets, one of which will be located in each of the main circuits; or by employing two main circuits, each provided with a polarized relay and a local circuit, any one of eight magnets may be selected and energized by no more than two impulses. An organization of this character is shown in Fig. 11. In this case two main circuits, B B', are employed, each of which includes a polarized relay, A and A', which operate circuit-closers 10 11 10^a 11^a, which are respectively included in local circuits i' i^2 i^3 i' , which are supplied with batteries 9^a 9^b, and respectively include the magnets C D E F, which operate four switch-bars and their switches 13, &c., in the same manner as already described. The local circuit i , through which the magnets 1 2, &c., are energized, includes a circuit-closer, 56, which is operated by the armature of the magnet C to close the circuit whenever that magnet is energized, and the circuit i is provided with branches i^5 i^6 i^7 , which respectively include circuit-closers 57 58 59, which are similarly operated by the armatures of the magnets D E F.

The operation of the system when thus organized is as follows: To select and energize the magnet 1, a - impulse will be sent over each of the main circuits B B'. These impulses will be sent simultaneously and will operate both the circuit-closers 11 and 11^a to close the local circuits i^2 i^4 , and thus energize the magnets C E and shift the switches 13 15 into connection with the branches m a , and at the same time operate the circuit-closers 56 58 to close the circuit i and cause the magnet 1 to be energized. To energize magnet 2, a - impulse will be sent over circuit B and a + impulse over circuit B', for magnet 3 a - minus impulse over circuit B alone, for magnet 4 a + impulse over circuit B and a - impulse over circuit B', for magnet 5 a + over both B and B', for magnet 6 a + over B, for magnet 7 a + over B and a - over B', and for magnet 8 a + over B'.

What I claim is—

1. The combination, with a main circuit, of an auxiliary circuit having branches which include working-magnets, switches arranged to direct the current over the auxiliary circuit through the different branches, switch-magnets included in auxiliary circuits and connected to operate the switches, and connections between the main circuit and the switch-magnets, whereby different switch-magnets are energized by different conditions of the current over the main circuit, substantially as described. 80

2. The combination, with a main circuit including an electro-magnet, of an auxiliary circuit having branches which include working-magnets, a circuit-closer operated through the action of the magnet in the main circuit to close the auxiliary circuit, a switch mechanism for directing the current over the auxiliary circuit through different working-magnets, and switch-magnets also included in auxiliary circuits which are closed and broken through the action of the magnet in the main circuit, substantially as described. 90

3. The combination, with a main circuit including an electro-magnet, of an auxiliary circuit having branches which include working-magnets, a circuit-closer operated through the action of the magnet in the main circuit to close the auxiliary circuit, a switch connecting the auxiliary circuit to a plurality of branches, each of which has a switch connecting with a plurality of other branches which connect with said working-magnets, switch-magnets for shifting said switches, located in auxiliary circuits which are closed and broken through the action of the magnet in the main circuit, circuit-closers M N, located in the circuits of the respective switch-magnets and operating after each switch-magnet acts to break the circuit through that magnet and close the circuit through another, substantially as described. 100 105 110

4. The combination, with a main circuit including an electro-magnet, of an auxiliary circuit having branches which include working-magnets, a circuit-closer operated through the action of the magnet in the main circuit to close the auxiliary circuit, a switch mechanism for directing the current over the auxiliary circuit through different working-magnets, and switch-magnets also included in auxiliary circuits which are closed and broken through the action of the magnet in the main circuit, a catch mechanism for holding the switch mechanism in its shifted position, and a releasing-magnet, G, for operating said catch mechanism to release the switch mechanism, substantially as described. 115 120 125

5. The combination, with a main circuit including an electro-magnet, of an auxiliary circuit having branches which include working-magnets, a circuit-closer operated through the action of the magnet in the main circuit to close the auxiliary circuit, a switch connecting the auxiliary circuit to a plurality of 130

branches, each of which has a switch connecting with a plurality of other branches which connect with said working-magnets, switch-magnets for shifting said switches, located in auxiliary circuits which are closed and broken through the action of the magnet in the main circuit, circuit-closers M N, located in the circuits of the respective switch-magnets and operating after each switch-magnet acts to break the circuit through that magnet and close the circuit through another, a catch mechanism for holding the switches in their shifted position, and a releasing-magnet, G, for operating said catch mechanism to release the switches, substantially as described.

6. The combination, with a main circuit including a polarized relay, of an auxiliary circuit having branches which include working-magnets, circuit-closers operated through the action of said relay to close the auxiliary circuit through different branches, according to the polarity of the current, a switch mechanism for directing the current over the auxiliary circuit through different working-magnets, and switch-magnets also included in an auxiliary circuit which is closed and broken through the action of the relay, substantially as described.

7. The combination, with a main circuit including a polarized relay, of an auxiliary circuit having branches which include working-magnets, circuit-closers operated through the action of said relay to close the auxiliary circuit through different branches, according to the polarity of the current, a switch mechanism for directing the current over the auxiliary circuit through different working-magnets and switch-magnets also included in an auxiliary circuit which is closed and broken through the action of the relay, a catch mechanism for holding the switch mechanism in its shifted position, and a releasing-magnet, G, for operating the catch mechanism to release the switch mechanism, substantially as described.

8. The combination, with a main circuit including a polarized relay, of an auxiliary circuit having branches which include working-magnets, circuit-closers operated through the action of said relay to close the auxiliary circuit through different branches, according to its polarity, switches 13 14, connecting each of said branches with a plurality of branches, each of which has a switch connecting with a plurality of other branches which connect with said working-magnets, switch-magnets for shifting said switches, located in auxiliary circuits which are closed and broken through the action of said relay, and circuit-closers M N, located in the circuits of the respective switch-magnets and operating after each switch-magnet acts to break the circuit through that magnet and close the circuit through another, substantially as described.

65 9. The combination, with a main circuit including a polarized relay, of an auxiliary cir-

cuit having branches which include working-magnets, circuit-closers operated through the action of said relay to close the auxiliary circuit through different branches, according to its polarity, switches 13 14, connecting each of said branches with a plurality of branches, each of which has a switch connecting with a plurality of other branches which connect with said working-magnets, switch-magnets for shifting said switches, located in auxiliary circuits which are closed and broken through the action of said relay, circuit-closers M N, located in the circuits of the respective switch-magnets and operating after each switch-magnet acts to break the circuit through that magnet and close the circuit through another, a catch mechanism for holding the switches in their shifted position, and a releasing-magnet, G, for operating said catch mechanism to release the switches, substantially as described.

10. The combination, with a main circuit including an electro-magnet, of an auxiliary circuit including an auxiliary magnet, P, and having branches which include working-magnets, a circuit-closer operated through the action of the magnet in the main circuit to close the auxiliary circuit, a circuit-closer, O, included in the auxiliary circuit and operated by the auxiliary magnet to close the auxiliary circuit at intervals, a switch mechanism for directing the current over the auxiliary circuit through different working-magnets, and switch-magnets included in auxiliary circuits which also include the auxiliary magnet and which are closed and broken through the action of the magnet in the main circuit, substantially as described.

11. The combination, with a main circuit including a polarized relay, of an auxiliary circuit including an auxiliary magnet, P, and having branches which include working-magnets, circuit-closers operated through the action of the relay to close the auxiliary circuit through different branches, according to the polarity of the current, a circuit-closer, O, included in the auxiliary circuit and operated by the auxiliary magnet to close the circuit at intervals, a switch mechanism for directing the current over the auxiliary circuit through different working-magnets, and switch-magnets included in auxiliary circuits which also include the magnet P and which are all closed by the action of the relay, and circuit-closers M N, included in said auxiliary circuits with the respective switch-magnets and operated by the auxiliary magnet to close the circuits through the respective switch-magnets successively, substantially as described.

105 110 115 120 125 In testimony whereof I have hereunto set my hand in the presence of two subscribing witnesses.

JOHN BURRY.
